UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,842, dated October 24, 1893.

Application filed September 19, 1893. Serial No. 485,907. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of wreath-like ornaments placed equidistant over the 10 surface of the paper, with a festoon of small balls hanging from the lower side of each wreath and a circular figure arranged within it, as represented in the accompanying drawing.

15 In the upper portion of the design which forms the border, two sprays of leaves spring in opposite directions from the lower side of the wreath like ornaments and between the latter are conventionalized floral ornaments which are suspended from sprays of leaves. 20

What I claim is—

1. The design for wall paper herein shown and described.
2. In the design for wall paper the border herein shown and described. 25

Witness my hand this 15th day of September, 1893.

CHARLES BOOZE.
